UNITED STATES PATENT OFFICE.

JOHN LOUDON AND THOMAS SHAW, OF NEW YORK, N. Y.

MACHINE FOR POLISHING AND EQUALIZING THE NAP OR PILE ON THE SURFACES OF HATS.

Specification of Letters Patent No. 4,033, dated May 7, 1845.

To all whom it may concern:

Be it known that we, JOHN LOUDON and THOMAS SHAW, both of the city, county, and State of New York, machinists, have jointly 5 invented and made and applied to use certain new and useful improvements in the mechanical means of polishing and equalizing the "nap" or "pile" or exterior fibrous matter forming the surfaces of hats, said 10 improvements being intended to effect the same or a similar object to that obtained by the operation of a teazel in the manufacture of woolen-cloth goods and to raise the nap or pile in such a manner that it shall be 15 more permanent and handsome and easier to keep in order than when finished without the aid of these improvements for which we seek Letters Patent of the United States; and that the said improved mechanical 20 means and the construction and effect thereof are fully and substantially set forth and shown in the following description and in the drawing annexed to and making part of this specification, wherein—

25 Figure 1, is an end elevation, and Fig. 2, a general plan of the apparatus as the same has been invented and made and used by us, the like letters and numbers as marks of reference applying to the same parts in each 30 figure.

A, is the bed of a table or bench with legs *a* to carry the operative parts, *b*, *b*, are tie and bearing pieces, carrying a crank handle, and shaft *c*, this has, at the inner end, a 35 miter or bevel wheel *d*, taking into a second similar wheel *e*, which is mounted on a vertical shaft *f*, that also carries the driving wheel *g*, which takes into a pinion *h*, on the foot of a vertical mandrel shaft *i*, these 40 wheels and shafts are partly shown by dotted lines indicating their position beneath the bed A, in Fig. 2, but are shown more fully in Fig. 1.

The mandrel shaft *i* comes through the 45 bed A, to carry the hat block chuck *k* in the center of which is fixed a square tapered block to enter within shape blocks, made in the usual manner and placed around the inside of the hat to be operated on and serving with the tapered square on the chuck to hold the hat firmly and vertically in place the flanch of the chuck *k*, serving to support the brim of the hat.

A fixed standard *l*, carries an arm *m*, 50 movable by an eye around the top of the

standard *l*, but held in place for work by a pin 1, going through the eye of the arm *m* into the shoulder of the standard *l*, a mortise in the arm *l*, receives a vertical slide *n*, adjustable in place by a screw 2, and carrying at the lower end a horizontal brush *o* for the top of the hat. A secondary arm *p*, 55 is secured by an adjusting screw 3, to the end of the arm *m*, and is fitted with a descending arm *q* attached by a screw 4, the arm *q* has on it a chop piece *r*, and between the arm *q* and chop piece *r*, is placed one end of a flexible brush *s*, this end is to be there confined and held for use by two 60 screws 5, 5.

The flexible brush *s* is what is technically known in the trade as the looer and is to be made of any fit material such as hard stiff piled velvet or velveteen or strong worsted plush, or of bristles woven into any proper fabric, but the material of which this brush *s*, and the top brush *o*, are made must be suited to the quality of the hat under operation and the brush *s*, is to be made with a flanch in its lower edge to operate on the 65 upper side of the hat brim as shown in the drawing, a small line *t* is to be attached to the loose end of the flexible brush or looer *s* and go over a pulley in the standard *l*, and through a hole in the bed A, beneath 70 which a weight *v* operates to pull upon the flexible brush or looer *s*, and keep it in close contact with the hat on the chuck *k* the movable arm *m*, and secondary arm *p*, being set in a right line with each other, or at 75 a more or less deviation from a right line will enable the workman to inclose more or less of the hat crown within the brush *s*, or extend or contract the operation according 80 to the size of the hat.

When thus constructed and put to operate with a hat on the chuck block, the attending workman moving the crank handle *c*, communicates a very rapid but governable rotary motion to the hat on the chuck, and the friction of the top brush *o* and flexible brush *s*, will create a certain degree of heat in the material of the hat the extent of which will be controlled by the judgment of the workman but the effect is that the hat 85 is uniformly kept in an upright and permanent position while the projecting or outer ends of the furry or other fibrous matter on the surface of the hat will be loosened, so that the brushes will both raise and dis- 90 95 100 105 110

entangle them and place them relatively with each other in a full appearance and with a highly polished surface to the hat, and we recommend the mechanical means we have described for giving the proper rapidity of motion because they are more entirely under the control of the workman, than they would be if driven by any other or independent power at the same time we do not intend to confine ourselves to this specific means of giving motion to the mandrel, and hat block chuck, and hat, but to use such as practice may show to be best available, and we do not intend to claim any of the parts used herein, as our own and exclusive invention because each taken separately has been already used for various purposes. But

We do claim as new and of our own invention—

The application of the vertical hat block chuck, *h*, on the mandrel *i* driven in any

convenient manner beneath the bed *A*, in combination with the movable arm *m* secondary arm *p*, and descending arm *q*, with the chop piece *r*, when such application and combination are employed as the means of using the horizontal brush *o* and flexible brush *s*, for the purpose of polishing and equalizing the nap or pile or exterior fibrous matter forming the surfaces of hats the whole constructed and operating substantially as herein described.

In witness whereof we the said JOHN LOUDON and THOMAS SHAW have severally hereunto set our hands and seals in the city of New York, this thirty-first day of December, in the year of our Lord one thousand eight hundred and forty-four.

JOHN LOUDON. [L. S.]
THOMAS SHAW. [L. S.]
